UNITED STATES PATENT OFFICE.

WALTER EVERETT MOLINS AND CYRIL BEST, OF LONDON, ENGLAND.

PRINTING MACHINERY.

Application filed January 10, 1928, Serial No. 245,741, and in Great Britain January 6, 1927.

This invention is for improvements in or relating to printing machinery and more particularly to a printing machine employing intaglio engraved rollers, and has for its object the provision of a machine which will enable a multi-coloured impression to be imparted to a travelling web of material without the possibility of the ink of one colour impression contaminating the ink of the next succeeding ink bath.

It has been found that with printing machines employing intaglio engraved rollers the ink of one colour impression before it is fully dried becomes deposited upon the printing roller of the next colour impression, so that after a long run the gradual accumulation of a series of deposits upon the said roller contaminates the ink bath of that roller with the result that all the colours with the exception of the first, become gradually changed and lose their clearness and in some cases the colour becomes completely altered.

Various devices have been proposed for removing the un-dried ink of one impression from the web prior to the web engaging with the next printing roller, but it has been found that all these devices have their defects, and that it is only possible to print by the intaglio process when the machine is travelling at a comparatively low speed.

It has been found, for example with a machine in which the web is run at a linear speed of approximately 200 feet per minute, that at least 12 feet is required between the succeeding printing rollers to enable the ink of one impression to be thoroughly dried before the web engages with the next printing roller, and it will be appreciated that with a minimum distance of this amount between successive printing units it is impossible to feed the web of paper in a straight line through the machine, due to the fact that the machine would become excessive in length in the case where two or three colours are to be printed.

It is an object of the present invention to provide means for printing simultaneously multi-coloured impressions upon a travelling web of material so that the ink of one impression will be thoroughly dried before the web engages with the next printing unit.

The present invention consists of a multi-coloured intaglio printing machine wherein a web of printing material drawn from a reel is controlled between the first and last

printing unit so as to follow a circuitous path constant in direction, (for example, clockwise or anti-clockwise) around the axis of the reel.

Further, the present invention consists of a machine for imprinting multi-coloured impressions upon a travelling web of material wherein the web is drawn from a reel around a series of guide rollers or the like, arranged to compel the web to follow a staggered or tortuous path through the machine and printing rollers, located at intervals along the path of the web, and adapted to imprint a series of coloured impressions upon one side of the web, the arrangement being such that between the first and the last printing rollers the guide rollers engage with only the un-printed side of the web and the printing rollers engage with only the printed side of the web, the printing rollers being spaced along the path of the web so as to permit each impression to dry before engaging with the next printing roller.

One method of carrying the invention into effect is illustrated diagrammatically in the accompanying drawing, and consists in mounting a reel of paper 1, above the bed 2 of the machine so that the reel is capable of rotating about a horizontal spindle 3 carried upon standards 4 mounted on the bed of the machine. Mounted to one side of the reel 1 is a cleaning gear 5 arranged to receive the web 7 and clean the same prior to the web receiving the first colour impression. From the cleaning gear 5 the web is carried over a guide roller 6 situated above the said cleaning gear and above and to one side of the reel 1, whereafter the web 7 is carried in a horizontal direction to the opposite side of the reel 1 and passes between a pressure roller 8 and a printing roller 9, where it receives its first colour impression. An ink duct 22 and furnishing roller 23 are provided beneath the printing roller to supply ink thereto. The web is thereafter carried around a guide roller 10 backwardly in a horizontal direction above the horizontal portion hereinbefore referred to, around a guide roller 11, located on the same side of the reel as the cleaning gear and downwardly to a guide roller 12 and thereafter to a second similarly constructed printing unit 13 located below the said reel and to one side thereof.

For the purposes of this invention it is to be understood that the web when it

reaches the second printing unit has "followed a circuitous path constant in direction around the axis of the reel" and may be thereafter carried through a cutting gear and severed into strips which are fed into a vertical stacking mechanism such as is described in specification No. 252,278. After receiving the second colour impression, however, the web may, if necessary, be carried in an upward direction over a guide roller 14 located above and to one side of the first printing unit, around the said guide roller and thereafter carried in a horizontal direction above the horizontal lengths of web hereinbefore referred to, around a further guide roller 15 situated above and to one side of the reel and downwardly around another guide roller 16 and a printing unit 17 situated below and to one side of the said reel 1 so as to enable the web to be brought into a horizontal direction in the manner hereinbefore described and fed, if necessary, through a further printing unit 18 towards the cutting mechanism 19 and a stacking mechanism 20. Thus it will be seen that by a further convolution around the reel as centre two further colour impressions may be imparted to the web.

Thus it will be seen that according to the present invention the web of printing material will follow a circuitous path which may be either clockwise or anti-clockwise in direction around the reel, such for example as a flat spiral, and the guide rollers controlling the path of the web are arranged to engage with only the unprinted side of the web and the printing rollers of the printing units engage with only the printed side of the web.

It will be appreciated that where the web of material in passing from one printing unit to the next printing unit has to move through a considerable distance, as would be the case if a fifth colour impression were required upon the machine illustrated, it would be possible after the impression of the fourth colour had been dried and prior to the application of the fifth colour, to pass the printed surface of the web over a roller or guide member without detrimentally affecting the appearance of the web, and it is to be understood that such an arrangement is included within the ambit of the present application. Further, instead of the printed web being fed to cutting and stacking mechanism, the web, after it has been printed, may be re-wound in the manner perfectly well known in the art.

Again, drying units may be mounted between the various printing units for the purpose of increasing the speed of the machine and embossing rollers may be provided for embossing the web during the printing operation.

Thus it will be seen that according to the

present invention, there is provided a printing machine wherein a web of material may be rapidly fed through a printing machine in which it is cleaned, preheated, printed and heated between colour impressions during its path through the machine without increasing the dimensions beyond the control of a single operator, and yet ensuring that each colour impression is dried before an additional impression is applied to the web. 75

What we claim as our invention and desire to secure by Letters Patent is:—

1. In a multi-color intaglio printing machine, the combination with a reel from which a web of printing material is drawn, of a series of rollers for guiding the web so arranged as to cause the web to travel in a circuitous path comprising a plurality of substantially complete circuits about the reel, a plurality of printing units spaced along the web and disposed in separate circuits of the path thereof, whereby the web is constrained to follow a circuitous path between adjacent units for permitting the ink of one impression to dry before the next impression is made. 80

2. In a multi-color intaglio printing machine, the combination with a reel from which a web of printing material is drawn, of a series of rollers for guiding the web so arranged as to cause the web to travel in a circuitous path comprising a plurality of substantially complete circuits about the reel, a plurality of printing units spaced along the web and disposed in separate circuits of the path thereof, whereby the web is constrained to follow a circuitous path between adjacent units for permitting the ink of one impression to dry before the next impression is made, said guide rollers being 95 disposed for engagement with the unprinted side of the web. 100

3. In a multi-color intaglio printing machine, the combination with a reel from which a web of printing material is drawn, of a series of rollers for guiding the web so arranged as to cause the web to travel in a circuitous path comprising a plurality of substantially complete circuits about the reel, the web moving in each circuit in the same 115 direction, and a plurality of printing units disposed at different levels in a vertical plane and spaced along the web, each unit being located in a separate circuit of the path of the web, whereby the web is constrained to 120 follow a circuitous path between adjacent units for permitting the ink of one impression to dry before the next impression is made. 125

4. In a multi-color intaglio printing machine, the combination with a reel from which a web of printing material is drawn, of a series of rollers for guiding the web so arranged as to cause the web to travel in a circuitous path comprising a plurality of 130

substantially complete circuits about the reel, the web moving in each circuit in the same direction, and a plurality of printing units disposed at different levels in a vertical plane and spaced along the web, each unit being located in a separate circuit of the path of the web, whereby the web is constrained to follow a circuitous path between adjacent units for permitting the ink of one

impression to dry before the next impression is made, said guide rollers being disposed for engagement with the unprinted side of the web, and an ink supplying duct located beneath each printing unit. 10

In testimony whereof we hereunto affix 15 our signatures.
